UNITED STATES PATENT OFFICE

132,380

DESIGN FOR AN ANTENNA HOUSING

George A. Page, La Grange, Ill., assignor to United Air Lines Transport Corporation, Chicago, Ill., a corporation of Delaware

Application February 10, 1942, Serial No. 105,746

Term of patent 14 years

To all whom it may concern:

Be it known that I, George A. Page, a citizen of the United States, residing at La Grange, in the county of Cook and State of Illinois, have invented a new, original, and ornamental Design for Antenna Housing, of which the following is a specification, reference being had to the accompanying drawing, forming a part thereof.

Figure 1 is a perspective view of an antenna housing embodying my new design;

Fig. 2 is an end elevational view of the antenna housing shown in Fig. 1;

Fig. 3 is a side elevational view of the antenna housing shown in Fig. 1; and

Fig. 4 is a top plan view of the antenna housing shown in Fig. 1.

The dominant features of my new design are shown in full lines in the drawing.

I claim:

The ornamental design for an antenna housing, substantially as shown and described.

GEORGE A. PAGE.
